UNITED STATES PATENT OFFICE.

EDWARD G. ASMUS, OF WAUWATOSA, ASSIGNOR TO JENNIE A. ZINNS, OF MILWAUKEE, WISCONSIN.

SAD-IRON.

SPECIFICATION forming part of Letters Patent No. 449,842, dated April 7, 1891.

Application filed October 2, 1889. Serial No. 325,778. (No model.)

To all whom it may concern:

Be it known that I, EDWARD G. ASMUS, of Wauwatosa, in the county of Milwaukee and State of Wisconsin, have invented certain new and useful Improvements in Sad-Irons; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to hollow self-heating sad-irons. Its main objects are to control the draft and prevent the overheating of the iron, and at the same time to provide a convenient rest or support therefor when it is not in use, and to simplify and cheapen the construction of the iron proper by dispensing with ordinary dampers.

It consists, essentially, of a hollow or chambered iron having draft-openings in the sides, a stand or rest with upturned sides adapted to receive and support the iron when not in use and to close the draft-openings therein, and of certain peculiarities of construction and arrangement hereinafter particularly described, and pointed out in the claims.

Figure 1 is a perspective view of my improved iron and stand or rest, the iron being placed in said stand so as to close the draft-openings. Fig. 2 is a vertical longitudinal section of the same. Fig. 3 is a perspective view of the stand or rest without the iron. Fig. 4 is a plan view of the gravitating latch by which the cover is locked when closed, and Fig. 5 is a sectional view showing a top view of the inwardly-projecting wings or ribs with which the iron is provided on the inside.

It has been ascertained in practice that when an iron is in use it is not necessary to close the draft, the temperature of the iron being kept down by contact with the clothes in ironing; but if the draft is left open when the iron is not in use it will become too hot. I therefore dispense with dampers attached to the iron itself and provide a stand or rest for holding the iron and closing the draft when it is not in use.

Referring to the drawings, A represents the

sad-iron proper, made hollow or chambered in the usual way to receive the fuel by which it is heated and provided in the sides near the bottom with draft-openings *a a*, which may be of any suitable form and size. For the purpose of holding the fuel away from the sides of the iron, so as not to choke or obstruct the draft and to prevent the escape of ashes, soot, &c., from the iron, I provide it on the inside with projections or wings *a' a'*, preferably placed in an inclined position above and close to the openings *a a*, which are preferably arranged, as shown, in corresponding positions.

C represents the cover, to which the handle D is attached in the usual or any suitable manner. It is hinged to the upper edge of the back of the iron, so as to turn upwardly therefrom at the point, and when closed to leave a space or openings between it and the upper edges of the iron.

E is an angular gravitating latch, pivoted at its angle to a post or upward projection *a'* on the point of the iron A and formed at one end with a thumb-piece *e*, serving also as a counter-weight, and at the other end with a foot *e'*, adapted to be turned down and held by the gravity of the thumb-piece *e* against the cover C, thereby holding it closed, an upturned lug *c* on said cover stopping the foot *e'* in the position in which it is shown in Figs. 1, 2, and 4. To release the cover C, the latch E is turned up into the position indicated by dotted lines in Fig. 2.

The iron is provided with a door F at the bottom of the rear end in the usual manner for the purpose of removing the ashes, and the bottom of the iron is preferably extended rearwardly in a flanged ledge *f*, against which the door F closes and which prevents ashes, &c., working through the door-opening from falling upon and soiling the work.

B is a rest or stand, having a reticulated or open-work bottom, through which the bottom of the sad-iron is exposed and its temperature thereby kept down. It is formed or provided with upturned sides *bb*, which close the draft-openings *a a* when the sad-iron is placed on the stand, as shown in Figs. 1 and 2, and it is preferably raised on short legs *b' b'*. This stand serves not only to control the draft of

and prevent overheating of the iron when it is not in use, but it affords a convenient support for holding the iron while not in use, some suitable device for the purpose being 5 indispensable in ironing.

I claim—

1. The combination, with a hollow sad-iron having draft-openings in the sides, of a stand adapted to close said openings when the iron 10 is placed thereon, substantially as and for the purposes set forth.

2. The combination, with a hollow sad-iron having draft-openings in the sides, of a rest having a reticulated bottom and upturned 15 sides adapted to close said draft-openings when the iron is placed on the stand, substantially as and for the purposes set forth.

3. A hollow sad-iron having draft-openings in the sides and having inclined inwardly-projecting ribs on the inside of the iron itself close to and overhanging said draft-openings, whereby the fuel is held away from the sides of the iron and ashes falling on said ribs are conducted thereby to the bottom of the iron and prevented from escaping 20 through said draft-openings, substantially as and for the purposes set forth.

In testimony that I claim the foregoing as my own I affix my signature in presence of two witnesses.

EDWARD G. ASMUS.
